UNITED STATES PATENT OFFICE.

HENRY B. NICHOLS, OF PHILADELPHIA, PENNSYLVANIA.

RAILWAY-SWITCH.

SPECIFICATION forming part of Letters Patent No. 625,458, dated May 23, 1899.

Application filed March 21, 1899. Serial No. 709,931. (No model.)

To all whom it may concern:

Be it known that I, HENRY B. NICHOLS, a citizen of the United States, residing at the city of Philadelphia, in the county of Philadelphia and State of Pennsylvania, have invented certain new and useful Improvements in Railway-Switches, of which the following is a specification.

My invention has relation to a railway-switch, and more particularly to that type or character adapted for use for street-railways, and in such connection it relates to the construction and arrangement of such a switch.

The principal objects of my invention are, first, to provide in a street-railway switch a tongue having its heel provided with a downwardly-projecting boss preferably integral therewith, said boss extending into the base-plate of the switch, in conjunction with a cover-plate formed on its upper face with the necessary ridges and depressions to constitute the converging continuation of the meeting rails, said cover-plate extending over the tongue a considerable distance, but only in contact with said tongue at its forward edge to afford an additional bearing for the switch-tongue beyond its point of pivotal connection with the switch-block, whereby the pivotal point of the switch is relieved of strain and accidental turning of the tongue by the thrust of the flange of car-wheels is avoided; and, second, to provide in such a switch, in conjunction with the depressed and ridged cover-plate, openings in the plate in the depressed portions thereof, and the said openings increasing in taper from the base on the under side of said plate to the top on the upper depressed portion of said plate, whereby accumulations of extraneous matter beneath said plate about the heel of said switch will be forced upward by the manipulations of said switch through said tapered openings, and thereby said switch about the heel portion maintained always in good and easy working condition.

My invention, stated in general terms, consists of a railway-switch constructed and arranged in substantially the manner herein-after described and claimed.

The nature and scope of my invention will be more fully understood from the following description, taken in connection with the ac-

companying drawings, forming part hereof, in which—

Figure 1 is a top or plan view of a street-railway switch embodying main features of my present invention. Fig. 2 is a similar view, enlarged, of that portion of the switch at which the cover-plate is secured. Fig. 3 is a top or plan view of the cover-plate removed from the switch. Fig. 4 is a side elevational view of Fig. 3, looking toward the left side of the cover-plate. Fig. 5 is a similar view looking toward the right side of said plate. Fig. 6 is a cross-sectional view on the line 6 6 of Fig. 2. Fig. 7 is a longitudinal sectional view on the line 7 7 of Fig. 2; and Figs. 8 and 9 are cross-sectional views, enlarged, taken, respectively, on the lines 8 8 and 9 9 of Fig. 1.

Referring to the drawings, *a* represents the switch-block, forming a continuation or connection between the main or straight rail *b* and the branch or curve rail *d*. The block *a* is recessed, as at *a'*, in which recess the tongue *e* of the switch is adapted to oscillate. This tongue *e* at its heel portion is provided with a downwardly-projecting boss *e'*, forming the pivot for the tongue, and this boss *e'* fits into a corresponding recess in the base *a'* of the switch-block *a*. The heel of the tongue *e* has its upper face cut away, as at *e*², to receive a cover-plate *f*, which fits over the tongue *e* and is pivotally secured to the switch-block *a*, and there is left a sufficient space between said tongue and a certain portion of said plate, so as to prevent friction between said tongue and plate, and the said plate is only in contact with said tongue at the forward edge *e*³ thereof, so as to afford an additional bearing for the switch-tongue beyond its point of pivotal connection with the switch-block. This cover-plate *f* has an angular side *f'*, adapted to register with the bias ends of the rails *b* and *d*, and it also has a curved side *f*² extending on the heel portion of the tongue *e* a considerable distance beyond the pivot *e'* of said tongue. The tongue *e* at its countersunk portion *e*² is adapted to swing around the curved side *f*² of the cover-plate. The plate *f* has on its upper face two depressions *f*³ and *f*⁴ and two ridges *f*⁵ and *f*⁶, forming a continuation of the two converging rails *b* and *d*, so as to permit the flange of the wheel of the vehicle

to travel over the plate f in either of said depressions f^3 or f^4 , while the periphery of said wheel bears upon either of the ridges f^5 or f^6 . In the depressions f^3 and f^4 are arranged the 5 vertical tapering openings g and g' , extending through the cover-plate f and toward its curved side f^2 . These openings g and g' are adapted to permit of accumulating dirt or other extraneous matter in and about the heel 10 portion of the switch to be forced through the said openings by the manipulations of the said switch and readily removed from the depressions f^3 and f^4 of the cover-plate f . By extending the curved end f^2 of the cover-plate 15 f a considerable distance beyond the point at which the heel of the switch is pivoted and so as to contact with the switch at its forward edge e^3 only the said pivotal point of the switch is relieved of strain and likewise is 20 prevented accidental turning of the tongue by the thrust of the wheels of a car or other vehicle, since the car or other wheels are carried by my construction and arrangement of a switch along the cover-plate f of the switch 25 far in advance of the pivotal point of the switch.

Having thus described the nature and objects of my invention, what I claim as new, and desire to secure by Letters Patent, is—

30 1. In a railway tongue-switch, a switch-block, a tongue having its heel portion countersunk at its upper face, a boss depending from the lower face of said countersunk heel portion and adapted to enter the switch-block 35 to pivot the tongue thereto, and a cover-plate having on its upper face ridges and depressions to form continuations for the meeting rails of the switch, said cover-plate adapted 40 to be secured to the switch-block over the countersunk portion of the tongue and said

cover-plate extending over said tongue a considerable distance, but only in contact with said tongue at its forward edge to afford an additional bearing for the switch-tongue beyond its point of pivotal connection with the 45 switch-block, whereby the pivotal point of the switch is relieved of strain and also is prevented accidental turning of the tongue, substantially as described.

2. In a railway tongue-switch, a switch-block having a recess, a tongue pivotally connected to the switch-block and adapted to oscillate in its recess, said tongue having its upper face countersunk at its pivotal connection with the switch-block, a cover-plate 55 adapted to fit over the countersunk portion of the tongue and in contact therewith only at its forward edge to afford a bearing for the switch-tongue beyond its point of pivotal connection with said block, whereby strain on 60 the pivotal point of said switch is relieved and accidental turning of the tongue avoided, the upper surface of said cover-plate being provided with ridges and depressions to form a continuation for the meeting rails of the 65 switch, and vertical tapering openings formed in said cover-plate and so arranged as that by manipulation of said switch extraneous matter will be forced through said openings from about the heel portion of said switch 70 and be readily removed from the depressions of said plate, substantially as described.

In testimony whereof I have hereunto set my signature in the presence of two subscribing witnesses.

HENRY B. NICHOLS.
